GAME BOARD

Simon H. Keegan, Brooklyn, George Wroldsen, Douglaston, and Joseph M. Rhatigan, Brooklyn, N. Y.

Application August 3, 1948, Serial No. 42,214

1

This invention is a game board so constructed that it may be used for playing several kinds of games or simulated games. More specifically, the game board of this invention may be used for playing simulated base ball, bowling, shuffle board and horse collar.

The game board of the present invention is provided with an oval shaped rim around its outer edge for guiding suitable surface projectiles used in playing the various games involved.

A player shoots or propels the projectile along the right-hand side of the board where it contacts the curved bordering rim, causing the projectile to reverse its direction of travel and go into scoring pockets or to stop on designated areas or to knock down miniature tenpins or to bounce off a miniature baseball bat, into appropriate scoring pockets, in accordance with the particular game being played at the time.

The principal feature of the invention is that the element of skill is involved, means being provided whereby the player may control the path of the projectile. Such control of the projectile path is provided by a variably positionable fence, which may be set at various angles in the path of the projectile so as to deflect the projectile in the desired direction, in accordance with the wishes and skill of the player.

This fence is so placed that it is in effect a continuation of the bordering rim, so that the projectile, when it rounds the U-bend, engages such fence, and is deflected thereby in the desired direction, in accordance with its angular setting.

More particularly, this guiding fence is controlled by a two-armed lever with its arms extending approximately at right angles to each other, one arm engaging the fence for moving it and holding it in its desired angular setting, while the other arm is connected to a flexible cable or rod controlled by the hand of the player, whereby the player, by manipulation of the cable or rod, may vary the angular setting of the fence and thereby the path of the projectile, with each shot.

The invention will be further described in connection with the accompanying drawings wherein:

Fig. 1 is a plan view of a game board of the present invention;

Fig. 2 is an enlarged section on the line 2--2 of Fig. 1;

Fig. 3 is a view of the bat used;

Fig. 4 is a sectional view in enlarged perspective of one end of a game board of the present invention;

1 Claim. (Cl. 273-39)

2

Fig. 5 is a view on a small scale showing a board used for bowling;

Fig. 6 is a similar view showing a board in use for playing shuffle board.

Referring now to the drawings, the board comprises a base 2, above which is positioned, in spaced relation, the board 4, forming the playing surface. Base 2 could, if desired, be omitted, and the board 4 used as a base board for the apparatus. The front or player's end of the game board is wider than the other end. The two boards 2 and 4 are secured to and held in spaced apart relation by the U-shaped filler strip 6.

15 The game board is provided with a vertically positioned, up-standing rim or border 8, for confining the projectile to the playing surface.

The lower right-hand corner is provided with any suitable known type of projector or shooter 9 for shooting a ball, disk or other type of projectile according to the type of game played. The projectile could also be projected manually, if desired.

Coming now to the most important feature of 25 the invention, the board 4 is provided with a resilient fence or deflector 12, which is in the form of a vertically positioned strip, the right hand end of which is inset with respect to the rim 8 forming in effect a continuation of the inner 30 surface of said rim 8. This flexible fence 12 is resiliently mounted, as by rivets 14 or the like, to the inner surface of rim 8 so as to be movable outwardly of such rim, against the resiliency of the fence.

35 In order to control the movements of the fence 12 and for setting it in the desired angular position for deflecting the projectile in the desired direction, there is provided a two-armed lever, indicated generally at 15. This lever comprises 40 an arm 16 positioned behind or to the left of the fence 12, having an upstanding part 18 engaging against the back of the fence 12. Integral with arm 16 is a vertical off-set 20 which is pivoted in the two armed bracket 22 positioned 45 in a suitable cut-out in the filler strip 6.

Integral with the off-set 20 is the other arm 24 of the lever, extending at approximately right angles to the arm 16, but located in a lower plane, being located in the space between the boards 50 2 and 4, as shown in Fig. 2. A cord, cable or wire 26 is connected to the outer end of arm 24 and passes around a pulley 28 and thence below board 4, to the front thereof, and through a hole 30 in the front board 32, where its outer end 34 may be grasped by the left hand of the player. It is evident that a pull on the cable

26 will move deflecting fence 12 in a counter-clockwise direction for deflecting the projectile more and more to the right in accordance with the angular position assumed by fence 12. When the cord is released, the resilience of the fence 12 causes it to resume its normal position. In use, the player would pull the cable 26 a small amount and hold it with his thumb against the rim of hole 30, for fixing the angular position of the fence 12, and then would shoot the projectile manually or mechanically from 9 with his right hand. Instead of using a cable 26 and pulley 28, a light rod could be used, as is evident.

The parts so far described are used in playing the several games capable of being played with this board.

Base ball

Base ball is played as follows: One or more players may participate. The ball is delivered either by rolling manually or with the aid of a projector along the right side of the board around the rim to the flexible fence 12 which is bent by pulling on the cable 26 to give the necessary guidance so that the ball will cross the home plate H. The bat is swung at the ball, causing it either to enter one of pockets A to N, to remain on the board, or to be driven into fair ground and thence back into end pockets Q to X. The board is normally level and the ball bounces off various surfaces until it comes to rest. Three outs on the part of one team terminates its turn at bat. When each team has had three outs an inning has passed. Nine innings constitute a game. Extra innings may be played in the event of a tie. Typical plays have been set up for each pocket into which the ball may be driven. The progress of the game is determined by these plays which are described below.

For the game of base ball, a simulated diamond 36 is laid out. A miniature bat 38, provided with a vertical pivot 40 is positioned in a suitable socket at either side of the plate. Pivot 40 may be circular, moving in a circular hole so that it swings free. The opposing player swings the bat as desired as the ball comes toward the bat from the fence 12, for driving the ball into one of a series of pockets located near the smaller end of the board and numbered from A to N inclusive. If the ball drops into one of these pockets, the following plays are indicated:

- A. A home run.
- B. A three base hit, scoring all runners.
- C. A two base hit, scoring runners from second and third bases and advancing the runner from first to third base.
- D. A single, all runners advance one base.
- E. A sacrifice fly, runner on third base scores, runner on second goes to third, and runner on first holds his base.
- F. A single, same as D.
- G. A three base hit, same as B.
- H. A two base hit, all basemen score.
- I. A single, batter singles, baseman on third scores and baseman and second out at home. Baseman on first out at third.
- J. Batter safe at first, runner out at home plate, and others advance one base.
- K. A single, man on third scores, man on second is out at home and man on first goes to second.
- L. A two base hit, same as C.
- M. A two base hit, all runners score.
- N. An outfield fly, same as E.

If, however, the ball comes to rest on the sur-

face of the board, in the areas marked "Foul," "Single," "Out," etc., as it does in over half the plays such would determine that play; if the ball continues on into pockets Q to X inclusive at the front of the board, the play or score would be as marked on such pockets, as follows:

- Q. A three base hit, scoring all runners.
- R. A bunt, batter is out, the man on third base scores, the runner on second goes to third, and the man on first goes to second.
- S. The batter is safe at first, the runner on third base scores, the runner on second is out at third, and the runner on first goes to second.
- T. A home run.
- U. A home run.

- V. A single, all runners advance one base.
- W. A bunt, the batter is safe at first, the runner on third is out at home, the runner on second goes to third, and the runner on first goes to second.
- X. Batter flies out to catcher, all runners hold bases.

If the ball goes over the plate and the batter does not swing, and the ball enters an end pocket, it is a strike. If he swings and misses, and the ball enters an end pocket, it is a strike. If the ball is not over the plate and the batter does not swing, and the ball enters an end pocket, it is a ball. No play can take place in end pockets Q to X unless a ball has first been hit into fair territory and has thereafter reached one of these pockets. The batter may swing from right or left, as desired.

The bat 38 is pivoted to swing freely on a pivot 40 and is started spinning by the opposing player at the same time the other player shoots the ball or projectile at 9.

The game is scored in accordance with standard baseball playing rules, in accordance with the plays made and resulting scores, as determined by the final point reached by the ball on the several plays.

Bowling

When a board as shown in Figure 5 is used for bowling, miniature ten pins 52 are set up as shown in Fig. 5, and a ball or marble is shot or manually delivered, as before, and guided by the appropriate angular setting of the fence 12, as already described. Usually 2 or 3 balls will be delivered in each frame for ten frames.

Each player delivers one or two balls along the right side of the board to the flexible fence 12 which is bent by a pull on cable 26 to deflect the ball toward the ten pins. The player uses but one ball if he can bowl over all pins with that one. If not, he tries to with a second ball. Delivery of one or two balls constitutes a frame. Each player bowls ten frames. The scoring is done just as in the regular game of bowling, with "strikes," "spares," and total pins for three balls.

Shuffle board

Where the board is used for playing shuffle board, as shown in Fig. 6, an area 54 is marked off in zones corresponding to the usual shuffle board markings, a projectile 56 in this case being a sliding friction disk which is delivered manually and is guided by fence 12 in accordance with the skill of the player, stopping on appropriate scoring zones, as in shuffle board. Pockets Q, R, S, T are provided, as in Fig. 1.

The game may be played by two or four players. One side shoots red discs, the other green. The object of the game is to knock off the opponent's

discs and to remain on the playing board. A red disc is delivered manually along the right side of the board to the flexible fence where it is deflected to remain on the playing surface 54. Green shoots next and tries to knock the red disc off or to slide up in front of the red. Again red shoots, trying either to knock off green, slide in front of green, or advance any red disc on the board to a better scoring position. When all eight discs have been delivered, the color (red or green) nearest end pockets Q, R, S, T wins.

Scoring takes place as follows: Assume that green is nearest the end pockets Q, R, S, T. Then all green discs remaining ahead of reds count as follows: If any disc should hang over the end of the board, such disc counts 4 points. Any disc resting in area X counts 3 points. Any disc resting in area Y counts 2 points. Any disc resting in area Z counts 1 point. Assuming that a green disc is nearest end pockets Q-T, and that the next disc to it is red, then no additional green disc may count, regardless of how many may remain on the board. The player having the color that wins a particular round leads off first in the next round. In this case green, having won, goes first. The first team (red or green) reaching a total of twenty-one points wins the match. Any disc dropping into the end pockets Q-T is dead.

Horse collar

Horse collar is a modification of shuffle board. It is played with eight discs as in shuffle board. If each team consists of but one man, he will shoot 8 discs. If each team consists of two men, each man will shoot 4 discs. If each team consists of 3 men, the first man shoots 2 discs and the next two men shoot 3 discs apiece. If each team consists of 4 men, each man shoots 2 discs apiece. The players use the adjustable fence 12 for guiding the discs, as before. The object of this game is to keep as many discs on the playing surface 54, Fig. 6, as is possible and to cause at least one discs to come to rest in area marked X. If the player or team has failed to get at least one disc in area marked X, or to hang over the end of the board above pockets Q-T, then the score of that team for that particular inning is 0, which suggests "horse collar," the name of the game.

Assume, however, that one or more discs come to rest in scoring area X, then the score for that particular inning is computed as follows: All discs protruding over the end of the board, i. e., above pockets Q-T, count eight points each. All discs resting completely in area X count 3 points each. All discs resting completely in area Y count 2 points each. All discs resting in area Z count 1 point each. If a disc should rest on a line within the scoring area, the disc takes the value of the lower scoring area. Discs in pockets Q-T have

no scoring value. Total points scored in six frames or innings wins the game.

The invention is not limited to any particular method of play or scoring for any of the games described. These factors may be varied as desired.

While the invention has been described in some detail, it should be understood that the invention is not limited to the precise details shown, but may be carried out in other ways.

We claim:

A game board comprising a board providing a playing area for a surface projectile, an approximately U-shaped rim in the form of a vertical strip at the extreme outer edge of the board for confining the projectile thereto, said rim extending uninterruptedly around three sides of said board, a vertically positioned strip of resilient material having one vertical surface secured at one end thereof to the inner surface of said rim and inset into the rim so as to be flush with the inner surface thereof, said end being positioned adjacent the U-bend of said rim, the other end being free and normally resting against the inner surface of the rim, said rim being recessed behind said resilient strip, a two-arm lever, the arms of which are horizontal and connected by a vertical offset, said lever having one arm positioned in said recess and engaging the free end of said strip of resilient material, and having the other arm beneath the game board, and means including a flexible cord connected to said other arm of said lever for actuating the lever to bend said strip outwardly into the path of said projectile, the strip snapping back to its original position when said cord is released.
